United States Patent

Des. 242,004
Patented Oct. 26, 1976

242,004

TABLE

William G. Faber, Grand Rapids, Mich., assignor to
Imperial Imagineering Limited, Chicago, Ill.

Filed Jan. 15, 1975, Ser. No. 538,028

Term of patent 14 years

Int. Cl. D6—03

U.S. Cl. D6—175

Fig. 1

Fig. 2

Fig. 3

Fig. 4

FIG. 1 is a perspective view of the new and ornamental design of a table;

FIG. 2 is a side elevational view of the new and ornamental design, the side not shown being a mirror image of the side shown;

FIG. 3 is an end elevational view of the new and ornamental design; and

FIG. 4 is a top plan view of the new and ornamental design.

I claim:

The ornamental design for a table, as shown and described.
